His Attorney

UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING SYSTEM.

Application filed April 17, 1928. Serial No. 270,597.

My invention relates to railway signaling systems, and particularly to systems of the type involving polarized line circuits for the control of three-indication signals.

5 I will describe one form of system embodying my invention, and will then point out the novel features thereof in a claim.

The accompanying drawing is a diagrammatic view showing one form of system embodying my invention.

Referring to the drawing, the reference characters 1 and 1^a designate the track rails of a railway track along which traffic normally moves in the direction indicated by 15 the arrow. These rails are divided by insulated joints 2 to form a plurality of track sections C—D, D—E, etc. Each section is provided with a track circuit comprising a source of current 12 connected across the 20 rails at the exit end of the section, and a track relay connected across the rails at the entrance end of the section, each track relay being designated by the reference character T with a suitable exponent corresponding to 25 the location.

Associated with each track section is a polarized line relay designated by the reference character L with an exponent corresponding to the location, and also associated 30 with each track section is a slow-releasing relay designated by the reference character A with an exponent corresponding to the location. The line relay L for each section is controlled by the track relay for the same section and by pole-changing contacts on the slow-releasing relay A for the section next in advance. For example, the circuit for line relay L^c is from terminal B of a suitable source of current, through front 35 contact 4 of track relay T^d, front point of contact 8 of relay A^d, front contact 3 of track relay T^c, winding of relay L^c, and front point of contact 9 of relay A^d, to terminal O of the same source of current. The 40 current which is then supplied to relay L^c is of what I will term "normal" polarity, so that relay L^c is then energized in the normal direction, wherein its normal contact 6—6^a is closed. When relay A^d is open, but track 45 relay T^c is closed, the circuit for relay L^c is from terminal B, through the back point of contact 9 of relay A^d, winding of relay L^c, contact 3 of track relay T^c, and the back

point of contact 8 of relay A^d to terminal O. The current then supplied to relay L^c is of 55 reverse polarity, so that the reverse contact 6—6^b of this relay is closed. It will be noted that the circuit last traced for relay L^c does not include the front contact 4 of track relay T^d. The reason for this will be explained hereinafter, as well as the reason for the resistance 10 which is connected across contact 4.

Each relay A is provided with a circuit which includes front contact 5 of the associated line relay L, which circuit will be obvious from the drawing. It follows, that each relay A is energized whenever the associated relay L is de-energized.

Each track section is provided with a signal designated by the reference character S with an exponent corresponding to the location. Each of these signals comprises a proceed lamp G, a caution lamp Y, and a stop lamp R. Referring to signal S^c, for example, the circuit for the proceed lamp G is from terminal B, through front point of contact 7 of the slow releasing relay A^c, normal contact 6—6^a of relay L^c, and lamp G to terminal O. The circuit for the caution 70 lamp Y includes front point of contact 7 of relay A^c and the reverse contact 6—6^b of relay L^c. The circuit for the stop lamp R includes merely the back point of contact 7 of relay A^c.

The operation of the system is as follows: When the parts are not influenced by the presence of trains, each relay L is energized in the normal direction, so that all signals S indicate proceed. I will now assume that a train moving toward the right enters section C—D. This train opens track relay T^c, thereby deenergizing relay L^c, which in turn deenergizes relay A^c, with the result that signal S^c changes to the stop indication. As the train enters section D—E, it deenergizes relays T^d, L^d and A^d, so that signal S^d changes to the stop indication. The pole-changing contacts 8 and 9 of relay A^d are now reversed, so that as soon as 90 track relay T^c becomes energized, relay L^c will become energized in the reverse direction, with the result that signal S^c will change to the caution indication. After the train leaves section D—E, relays L^d and A^d 95 will become energized, so that relay L^c will

then be energized in the normal direction, and signal S^c will again give the proceed indication.

The foregoing explanation of the operation of the system contains no mention of the track relay contacts 4. The reason for these contacts, is as follows: Assuming that the circuit for relay L^c does not include contact 4 of track relay T^p , then when a light engine passes point D at high speed, track relay T^c might become closed before the front contacts of relay A^p become opened. Relay L^c would then be energized in the normal direction for a brief interval of time, with the result that proceed lamp G of signal S^c might be momentarily lighted, so that this signal would momentarily give the proceed indication. As soon as such light engine enters section D—E, however, contact 4 of track relay T^p will open before contact 3 of track relay T^c will close, with the result that the normal circuit for relay L^c is held open during the interval between the opening of relay T^p and the opening of the front contacts of slow-releasing relay A^p . This prevents momentary energization of relay L^c in the normal direction, and so prevents momentary lighting of the proceed lamp G of signal S^c . It will be noted that contact 4 of relay T^p is not included in the circuit for reverse energization of relay L^c , so that as soon as relay A^p opens, signal S^c changes from the stop indication to the caution indication.

In the absence of the resistance 10 across contact 4, if a train should enter section D—E from the exit end, or if a switch in this section should be opened, the opening of contact 4 of relay T^p would open the normal circuit for relay L^c before the reverse circuit would become closed at the back contacts of relay A^p , with the result that relay L^c would be de-energized, and the interval during which this relay is de-energized might be sufficient to permit the contacts of relay A^p to release, with the result that signal S^c might momentarily give a stop indication before changing to the caution indication. To avoid this possibility, I have connected a resistance 10 across the contact 4 of each track relay, and the parts are so adjusted that when line relay L^c , for example, is closed, it will remain closed with contact 4 open, provided, of course, that the circuit for relay L^c is closed at all other points. If relay L^c is open, however, it will not close in response to the current

which it receives through the resistance 10 when contact 4 is open. In other words, considering the normal circuit only for relay L^c , the parts are so adjusted that the current received by relay L^c when contact 4 is open, is greater than the release value of this relay but less than the pick-up value, whereas, when contact 4 is closed the current received by relay L^c is greater than its pick-up value. Assuming now that a train backs into section D—E, contact 4 of track relay T^p will open, but sufficient current will be supplied to relay L^c through resistance 10 to keep this relay energized, with the result that no change will occur in so far as relay L^c is concerned until relay A^p releases, whereupon, relay L^c will become energized in the reverse direction and signal S^c will change from the proceed indication to the caution indication.

Although I have herein shown and described only one form of system embodying my invention, it is understood that various changes and modifications may be made therein within the scope of the appended claim without departing from the spirit and scope of my invention.

Having thus described my invention, what I claim is:

In combination, a stretch of railway track divided into sections, a track circuit including a track relay for each section, a polarized line relay for each section, a slow-releasing relay for each section controlled by the associated line relay, a circuit for each line relay including a front contact of the track relay for the associated section and pole changing contacts of the slow-releasing relay for the section next in advance, each line relay circuit including a front contact of the track relay for the section next in advance which contact is interposed between the source of current and one of the pole changing contacts in such circuit, each line relay circuit also including a resistance connected across the last-mentioned track relay contact, the parts of each line relay circuit being so proportioned that when the last-mentioned track relay contact is open and the circuit is otherwise closed, the line relay will remain closed if it is already closed but will not close if it is open, and signals for the sections controlled by said line relays and slow-releasing relays.

In testimony whereof I affix my signature.
ROBERT M. GILSON.
